Patented Nov. 6, 1917.

FIG. 1.

FIG. 2.

Inventor:
John A. Frossard:

by his Atty.

Charles S. Gooding.

UNITED STATES PATENT OFFICE.

JOHN A. FROSSARD, OF PEPPERELL, MASSACHUSETTS.

SAFETY DEVICE FOR FEED-ROLLS.

1,245,698.

Specification of Letters Patent.

Patented Nov. 6, 1917.

Application filed August 22, 1916. Serial No. 116,361.

To all whom it may concern:

Be it known that I, JOHN A. FROSSARD, a citizen of the United States, residing at Pepperell, in the county of Middlesex and 5 State of Massachusetts, have invented new and useful Improvements in Safety Devices for Feed-Rolls, of which the following is a specification.

This invention relates to safety devices 10 for feed rolls and more particularly for rolls used on paper calendering machines. In such machines it is necessary that the paper be fed into the rolls by hand during which time said rolls are rotating at a very high 15 rate of speed. Unless great precaution is used in this operation the operator is very likely to get his fingers caught between said rolls and be badly mutilated.

The object of this invention is to provide a simple, inexpensive and efficient device including a guard adapted to be placed in front of each set of rolls of the machine, permitting the operator to insert his fingers between the rolls far enough to guide and 25 feed the paper until the same is caught and rotated by said rolls, without in the least endangering his hand and absolutely preventing his getting caught by said rolls.

Another object of the invention is to provide means for regulating the adjustment of the guard relatively to said rolls and prevent said guard from being inserted between said rolls far enough to be caught thereby.

The invention consists in the combination and arrangement of parts set forth in the following specification and particularly pointed out in the claims.

Referring to the drawings:

Figure 1 is a vertical section taken 40 through a paper calendering machine, illustrating portions of three rolls of said machine in section with a device embodying my invention shown in connection therewith.

Fig. 2 is a plan view of one of the safety devices illustrated in Fig. 1.

Like numerals refer to like parts in both views of the drawings.

In the drawings 3, 4 and 5 preferably represent the rolls of a calendering machine and 6 a strip of paper which is to be calendered by said rolls. The rolls 3, 4 and 5 may be mounted in any suitable manner or 50 in accordance with the usual method of mounting rolls in calendering machines, these movable slightly relatively to each

other so as to provide suitable pressure upon said paper, said rolls being supported in side frames 7 and 8.

The device embodying my invention includes a support 9 preferably consisting of an angle bar 10, one of which is arranged longitudinally of each pair of rolls and in front of said rolls, said bar being supported at opposite ends by brackets 11, 11 adjustably secured to the side frames 7 and 8. The bars 10 are adjustably secured by means of clamping plates 12, 12 to said brackets 11 and they are further positioned with respect to said rolls by stops 13, 13. Each of the 70 angle bars 10 is arranged with one leg substantially horizontal as at 14 and directed toward the pair of rolls in front of which said angle bar is supported.

To one face of the leg 14 of said angle 75 bar a plurality of guards 15, 15 are secured preferably by screws 16, 16 extending through the leg 14 of said angle bar and said guards and into a strip of wood 17 which extends substantially the length of 80 said series of guards. The guards 15 are furthermore preferably formed of resilient sheet material such as fiber and are disposed between their respective rolls; the inner ends 18 of said guards may extend as far into 85 the crease or space 19 between the pair of rolls in front of which said device is arranged as will be possible without touching either of said rolls.

In the present instance the edge 18 is 90 slightly nearer the lower roll than the upper roll, thus providing ample space for the paper 6 to be inserted between the end of said guard and the upper roll. Means are provided along the edge 18 preferably consisting of a ridge 20 forming a shoulder 21 the convex surface of said ridge being disposed toward the paper 6 so as to provide a smooth edge adapted to assist in inserting the paper between the rolls.

The shoulder 21 is arranged in such a position relatively to the upper roll that when the fingers of the operator's hand are inserted between said rolls, the nails of said fingers contact with said shoulder and prevent a further insertion thereof between said rolls thereby preventing said fingers from contacting with both of the rolls of the pair.

The position of the fingers at this time is 110 illustrated in dotted lines in the lower left hand portion of Fig. 1 in which position the

paper 6 is being fed to the rolls 4 and 5 it having already been fed to the rolls 3 and 4, said rolls being arranged to turn in the direction of the arrows, *a*, *a*, and *b*, *b*. The space shown at 22 is ample for inserting the paper over the ridge 20 and between the two rolls adjacent thereto, but this space is too small to permit the fingers of the operator to be inserted therethrough, and in consequence of this arrangement it will be impossible for the operator to move his fingers so that they will engage both of the rolls, but when said fingers are engaging but one of said rolls and a stationary device, as for instance the guard 15, no possible harm can result.

When the safety device is being placed in position in front of its respective pair of rolls and the stops 18 have not been properly adjusted there is great danger of inserting the ridged end of the guards 15 so far between the rolls that said guard will be caught thereby and carried through said rolls, thus destroying said device. To guard against this possibility a series of stops 23, 25 have been provided which are preferably secured to resilient members 24 which, in turn, are attached to the leg 14 of each of the angle bars 10 by screws 25.

These stops are provided with rounded faces 26 and so placed with respect to the guard members 15 that as said safety device is being placed in position in front of its respective pair of rolls the rounded portion 35 26 thereof will contact with the adjacent face of the roll thereabove before the ridge 20 has a chance to engage both the rolls above and below the same and after said stop 26 has engaged the roll thereabove it 40 is withdrawn a slight distance sufficient to permit the paper 6 to pass between the rounded end 26 thereof and the roll nearest to said stop.

The stops 23 are narrow as will be seen by 45 referring to Fig. 2, and at substantial distances apart to permit the operator's hand to be inserted between said stops until his finger nails engage the shoulder 21, the rounded surfaces 26 being so arranged that 50 they assist in the insertion of the paper between said stops and said rolls.

As previously stated, the invention is broadly adapted for use in connection with 55 paper calendering machines, although it is to be understood that the same is not limited to such an application but may be applicable to any machine employing feed rolls where in the work is fed to said rolls when the same are in operation.

Furthermore, the guard members are 60 preferably formed of resilient sheet material which are ridged at the free edges thereof and pressed to present a convex surface to the roll against the surface of which

the paper is in contact, but other forms of 65 guard may be employed capable of accomplishing the same result without departing from the spirit and scope of the invention.

Having thus specifically described my invention what I claim and desire by Letters 70 Patent to secure is:

1. The combination of a pair of feed rolls, a guard disposed between said rolls and yieldable relatively thereto, and a ridge arranged along the edge of said guard adjacent to said rolls and extending substantially the full length of said rolls adapted to prevent the insertion of the operator's fingers between said rolls during the feeding of the material thereto. 80

2. The combination of a pair of feed rolls, a guard yieldingly mounted between and directed toward said rolls, and a ridge formed along the edge of said guard adjacent to said rolls, said ridge being of uniform shape substantially the length of said guard and constructed and arranged to be engaged by the nails of the operator's fingers to prevent said fingers from being drawn between said rolls. 85

3. The combination of a pair of feed rolls, a guard yieldingly mounted adjacent to said rolls, adapted upon yielding to contact with one of said rolls, said last named roll forming a stop to limit the distance to which said 95 guard can move when yielding, and means disposed along the edge of said guard adjacent to said rolls adapted to prevent the operator's fingers from being drawn between said rolls. 100

4. The combination of a pair of feed rolls, a support disposed longitudinally and in front of said rolls, said support being adjustable toward and from said rolls, a guard mounted on said support directed between 105 said rolls, and means yieldingly mounted on said support adapted to engage one of said rolls to limit the insertion of said guard between said rolls.

5. In combination, a pair of feed rolls, a support arranged longitudinally and in front of said feed rolls, a plurality of resilient guard members secured side by side to said support and directed between said rolls, and means disposed adjacent to the 110 edges of said guard members adjacent to said rolls adapted to prevent the operator's fingers from being drawn between said rolls during the feeding of paper therethrough. 115

6. In combination, a pair of feed rolls, a support disposed in front of said feed rolls and adjustable toward and from said rolls, a guard mounted upon said support and directed between said rolls, and stops yieldingly disposed at intervals along said support, said stops being constructed and arranged to prevent the insertion of said guard 120 between said rolls. 125

7. In combination, a pair of feed rolls, an angle bar arranged in front and longitudinally of said rolls, one leg of said angle bar being directed toward said rolls, a yieldable 5 guard member secured to said leg and directed toward said rolls, means for securing said guard to said bar, and a ridge disposed longitudinally of the edge of said guard adjacent to said rolls adapted to prevent the

operator's fingers from contacting with both 10 of said rolls.

In testimony whereof I have hereunto set my hand in presence of two subscribing witnesses.

JOHN A. FROSSARD.
